ABSTRACT: In a switching system, a scanning arrangement is provided to interrogate a plurality of links interconnecting a plurality of switching stages of the system for determining their busy and idle conditions. The scanning arrangement includes a plurality of diode-gating means responsive to the interrogating signals for applying the busy and idle status signals of the links to the register means of the system wherein each of said diode-gating means is coupled to the scanning means and the register means and to a corresponding one of the plurality of links. Each of the diode gating means includes a DC potential source, a junction, first resistor coupling the DC potential source to the junction, second resistor coupling the junction to the corresponding link, a capacitor coupling the scanning means to the junction, and a diode being coupled to the junction and being poled to change from a nonconductive to conductive state in response to the change in the condition of the corresponding link from an idle to busy condition. The system is also provided with a plurality of biasing means, each means establishing a predetermined common bias potential level at the output of a selected number of the plurality of the diode-gating means.

SCANNING ARRANGEMENT IN A TELEPHONE SWITCHING SYSTEM

BACKGROUND OF THE INVENTION

1. Field of the Invention

The present invention relates to a scanning arrangement in a telephone-switching system for determining the free or busy conditions of the links interconnecting the switching stages of the system, in general, and more particularly, to an improved scanning arrangement having gating means coupled to the links for testing their free or busy conditions.

2. Description of the Prior Art

In accordance with the prior art such as British Pat. No. 981,908, a plurality of links interconnecting a plurality of switching stages are scanned by a scanning arrangement having a plurality of gating circuits respectively coupled to the links. According to the patent, the gating circuits include magnetic cores which are arranged with discrete electrical components. Such an arrangement has been found rather complex and expensive.

SUMMARY OF THE INVENTION

It is an object of the present invention to provide an improved scanning arrangement which overcomes the aforementioned shortcomings of the prior art.

In accordance with the invention, there is provided a scanning arrangement in which each of the gating circuits includes first and second resistances, a capacitance and a diode, each with a common terminal, the other terminals of said first and second resistances being connected to the associated link and to a first DC potential respectively, the other terminal of said diode, which constitutes the output terminal of said gate, being coupled to a second DC potential while the other terminal of said capacitance is connected to said pulse source, and that the state of conductivity of said diode is reversed when an interrogation pulse is applied to said gate and simultaneously the associated link is in a predetermined one of its two states.

According to another characteristic of the present testing arrangement, the ratio of said first and second resistances of each gate is chosen to approximatively obtain the same predetermined potential at their common terminal when the associated link is busy and irrespective of the link type when each type is characterized by a different value of busy potential.

The present invention also relates to a matrix arrangement in which a column circuit is coupled to a plurality of row conductors via respective unidirectional impedances.

Such a matrix arrangement is well known in the art but presents a relatively high leakage capacitance. Therefore it is a further object of the present invention to provide a matrix arrangement of the above type which does not present the mentioned drawback.

The present matrix arrangement is characterized by the fact that said column circuit includes m column conductors each associated with a corresponding group of said row conductors and that said m column conductors are connected in common to the input of an output amplifier via m respective second unidirectional impedances.

The above mentioned and other objects and features of the invention will become more apparent and the invention itself will be best understood by referring to the following description of embodiments taken in conjunction with the accompanying drawings in which:

BRIEF DESCRIPTION OF THE DRAWINGS

FIG. 1 shows a testing arrangement in accordance with the invention, for testing the free and busy states of the links of a telephone exchange switching network;

FIG. 2 shows in detail part of a column circuit of the arrangement of FIG. 1;

FIG. 3 schematically represents a path between a subscriber's line circuit and a junctor circuit in the switching network of FIG. 1, as well as the marking switches associated thereto;

5 FIG. 4 shows some marking pulse waveforms involved in the establishment of the path of FIG. 3.

DETAILED DESCRIPTION OF THE INVENTION

10 Referring to FIG. 1, the testing arrangement shown therein comprises a matrix. The matrix is made of an array of crossover points formed by n planes each having m rows, where each of the m rows are crossed by k columns and where m , n , and k are integer numbers. The matrix is thus a three-dimensional one formed by crossover points made by k , by m , by n intersecting crossover points. The m by n row wires of the matrix are divided in m groups of n row wires X_{11} to X_{1n} to X_{mn} and the row wires of each of these m groups are coupled to the k matrix outputs P_1 to P_k via k corresponding column wires Y_{11} to Y_{1k} to Y_{im} to Y_{mk} and associated decoupling diodes D_{11} to D_{1k} to D_{im} to D_{mk} . The free ends of the row wires X_{11} to X_{mn} of the above matrix are connected to respective ones of the lmn outputs of a scanning circuit SC. Each of the k outputs P_1 to P_k of a matrix is connected to a corresponding input of a register circuit REG via the cascaded connection of a buffer amplifier BA_1 to BA_k and a column amplifier A_1 to A_k respectively, the column amplifiers A_1 to A_k and register REG being common to the matrix of the testing arrangement. The crosspoints of the row wires X_{11} to X_{mn} and column wires Y_{11} to Y_{mk} are each constituted by a gating circuit comprising four elements which have a common terminal: a capacitor C_1 , a diode W_1 and two resistors R_1 and R_2 . The free end of capacitor C_1 and the cathode of diode W_1 are connected to their associated row and column wires respectively, whereas the free ends of resistors R_1 and R_2 are connected to an associated link (not shown) of a switching network SN and to a source of positive DC potential E_1 respectively.

40 Each of the column wires Y_{11} to Y_{mk} of a matrix is further connected to a source E_2 of positive DC potential via a respective series connection of a diode W_2 and a resistor R_3 ($R_3=1,300$ ohms). The matrix of the testing arrangement moreover includes an additional row X_1 which serves for checking purposes as it will be described later. This row X_1 is connected to one column wire, e.g. Y_{11} to Y_{1k} , out of each of the k sets of m column wires leading to a corresponding matrix output P_1 and P_k , via a respective crosspoint gating circuit comprising three elements with a common terminal. The crosspoint gates associated with row X_1 each comprise a capacitor C_2 ($C_2=C_1$), a diode W_3 and a resistor R_4 ($R_4=150$ kilohms), the free terminals of capacitors C_2 and the cathodes of diodes W_3 being connected to row wire X_1 and to column wires Y_{11} to Y_{1k} , respectively. The free ends of resistors R_4 are connected to the source E_1 of positive DC potential.

55 FIG. 2 shows the detailed circuitry of the buffer and column amplifiers BA_i and A_i respectively ($i=1$ to k). The buffer amplifier BA_i comprises an NPN transistor Q_1 mounted in the emitter follower configuration. The base of transistor Q_1 is connected, on the one hand to its emitter via a resistor R_7 , and on the other hand directly to the output P_i of the matrix associated with the amplifier BA_i . The collector of transistor Q_1 is connected to a source E_3 of positive DC potential via a resistor R_6 . The parallel connection of the outputs of the 1 homologue buffer amplifiers BA_i ($i=1$ to k), which are respectively associated to the matrix of the testing arrangement, is connected to ground via a resistor R_5 in series with the parallel connection of a resistor R_8 and a capacitor C_4 , resistors R_8 and R_5 and capacitor C_4 forming part of the common output amplifier A_i . The latter amplifier A_i comprises two NPN transistors Q_2 and Q_3 . The base of transistor Q_2 is connected directly to the junction of resistors R_8 and R_5 and to its emitter via a diode W_4 , the common connection of the anode of diode W_4 and the emitter of transistor Q_2 being connected to the source E_2 . The collector of transistor Q_2 is connected to the

source E_3 of positive DC potential and to the source E_2 via a resistor R_9 and a resistor R_{10} respectively and to the base of transistor Q_3 via a capacitor C_5 . The transistor Q_3 has its emitter connected to ground and its base further connected to the source E_2 via a resistor R_{11} . The collector of transistor Q_3 which constitutes the output of column amplifier A_1 is connected on the one hand to the 1-input of a corresponding bistable device (not shown) of register REG and on the other hand to the source E_2 via a resistor R_{12} .

FIG. 3 schematically shows a path between the cutoff relay Cor of a subscriber's line circuit LC and a junctor circuit JC in the switching network SN wherein the subscriber's line circuits and the junctors are intercoupled through four cascaded switching stages which are themselves intercoupled via links. The path between the cut off relay Cor and the junctor circuit LC may be established through these four cascaded switching stages and more particularly through the four relays Ar , Br , Cr , Dr and their make contacts ar , br , cr , dr included in these switching stages respectively. Hereby contact ar interconnects the relays Cor and Ar , contact br the relays Ar and Br , contact cr the relays Br and Cr and contact dr the relays Cr and Dr . The links between relays Ar - Br , Br - Cr and Cr - Dr are referred to as, la , lb , lc (links $-a$, $-b$, $-c$) respectively. The other ends of relays Dr and Cor are connected to ground via the series connection of a decoupling diode W_6 and the make contact jr of a relay Jr of the junctor circuit JC, and to a source E_4 of negative DC potential respectively. The junction point of the cathode of diode W_6 and relay Dr is connected to the emitter of an NPN switching transistor TJ , via the series connection of a resistor R_{14} and the make contact mr_1 of a relay Mr (not shown) associated to junctor JC. The collector of transistor TJ is connected to a source E_5 of positive DC potential via a current source I . The junction point of contact ar and relay Ar (contact br and relay Br , contact cr and relay Cr , contact dr and relay Dr) is connected to the collector of an NPN switching transistor TA (TB, TC, TD) via a decoupling diode GA (GB, GC, GD). The emitters of transistors TA , TB , TC , TD are connected to ground, whereas their bases ta , tb , tc , td , as well as the base tj of transistor TJ are connected to respective outputs of a path marking circuit (not shown). The relay Jr has one of its two ends connected to ground and its other end coupled to the source E_4 via the make contact mr_2 of the above relay Mr . The links la , lb , lc of the above path are connected to three corresponding resistors R_1 of the testing arrangement of FIG. 1, previously described.

FIG. 4 is a diagram representing the pulse waveforms ta , tb , tc , td , tj , applied by the above-mentioned path-marking circuit to the corresponding base electrodes of the switching transistors TA , TB , TD , TJ , during the establishment of the connection between the line circuit LC and the junctor circuit JC. The function of these waveforms will hereinafter be explained together with the principle of operation of the whole arrangement.

When the above path-marking circuit receives from a central processor (not shown) of the exchange the order to establish the path of FIG. 3, it energizes the above relay Mr associated to the junctor JC. The energized relay Mr closes its make contacts mr_1 and mr_2 , the closure of make contact mr_1 interconnecting the emitter of transistor TJ and resistor R_{14} and the closure of make contact mr_2 causing the energization of relay Jr . At the same time the pulse tj , which has a width T equal to the marking period of the path, is applied to the base tj of the normally cutoff transistor so that this transistor TJ is switched to the conductive condition. A positive potential E_5 is thus applied to the junction point of diode W_6 and relay Dr so that diode W_6 is blocked. The latter diode decouples the termination of the path LC-JC from the ground which is connected thereto via closed contact jr of relay Jr . After the start of application of pulse tj , pulses td , tc , tf , ta of equal width with respect to each other are consecutively applied to the corresponding bases of transistors TD , TC , TB , TA , the trailing edge of first applied pulse td coinciding with the leading edge of last applied pulse ta . In this way relays Dr , Cr , Br and Ar are energized one after another via their associated

diodes GD , GC , GB , GA and transistors TD , TC , TB , TA . The energization of relay Ar and the subsequent closure of contact ar causes the energization of cutoff relay Cor of the relevant line circuit LC. At the end of pulse tf , i.e. of the path marking period T , transistor TJ is switched back to its cutoff condition. Due to transistor TJ being switched off and the connection from cathode of diode W_6 to source to source E_4 being established, the latter diode W_6 becomes conductive and the path LC-JC is held by the closed make contact jr of relay Jr .

10 The above relay Mr which controls relay Jr via contact mr_2 is held operated until the end of the busy condition of its associated junctor circuit JC. The release of path LC-JC, established as above, is performed by releasing this relay Mr . Contact mr_2 of the released relay Mr breaks the holding path of relay Jr , thus causing the release thereof and hence the opening of its make contact jr . Due to the connection LC-JC being broken by the opening of contact jr , relays Cor , Ar , Br , Cr , Dr are released.

20 It is to be noted that the links la , lb , lc , when in the busy state, are at different potentials with respect to one another, owing to the voltage drops across their associated relays in cascade. Obviously, the switching network SN includes other paths interconnecting circuits of different types of the telephone exchange, e.g. signalling circuits and outgoing junction circuits etc., but it can be so designed that the links of the switching stages of all these paths have busy state potentials substantially equal to the busy state potentials of the links la , lb , lc . The ratio of the potentiometer resistances R_1 and R_2 of

25 each gate of the testing arrangement of FIG. 1, is chosen in accordance with the type of the relevant link, i.e. with the busy state potential value of this link. For instance, for the a type links which have a busy state potential of about -13 volts, the resistances R_1 and R_2 are equal to 620 K. ohms and 240 K. ohms respectively. In this way, for all busy links and irrespectively of their type, the same potential of e.g. 0 volts is obtained at the junction point of the resistances R_1 and R_2 in each of the gates correspondingly associated thereto. When a link of

30 switching network SN is in the free state, in which both ends of the link are floating, it is obvious that the potential at the junction point of the resistances R_1 and R_2 of its associated gate is equal to that of the source E_1 positive potential, e.g. +5 volts, connected thereto via the above resistance R_2 .

35 It is to be noted that resistances R_1 and R_2 are of high value, in order to ensure a sufficient decoupling between the gating circuits of the testing arrangement matrices and the switching network SN.

40 The principle of operation of the testing arrangement of FIGS. 1 and 2 is as follows:

45 In the rest condition of the testing arrangement, all row wires X_{11} to X_{mn} , as well as row wire X_1 in the matrix thereof, are at the ground potential connected thereto via the output resistors (not shown) of the associated selection gates (not shown) included in the scanning circuit SC. The diodes W_1 of the gating circuits of the arrangement are in their blocked condition, since their anodes are at ground potential or at the positive potential of source E_1 (+5 volts) depending on their associated links being in their busy or free state respectively,

50 and their cathodes are at the more positive potential of source E_2 , e.g. +12 volts, applied thereto via resistors R_3 and decoupling diodes W_2 associated to each column Y_{11} to Y_{mk} . For the same reason diodes W_3 associated with row X_1 are in their blocking condition, too. Diodes D_{11} to D_{mk} are blocked since their anodes are biased at the positive potential of source E_2 via the series connections of R_5 and W_2 and since their cathodes are also biased at the same positive potential E_2 , via conductive diodes W_4 , resistors R_5 and R_7 . Transistors Q_1 and Q_2 are in the cutoff condition, since their base and emitter electrodes are at the same potential, whereas transistors Q_3 are conductive. Consequently the outputs of column amplifiers A_1 and A_k taken at the collectors of the respective transistors Q_3 are substantially at ground potential.

55 When a path has to be established through the switching stages of network SN, such as the path of FIG. 3 previously

described, the above-mentioned central processor of the exchange gives orders to the scanning circuit SC to enable the interrogation of the testing arrangement gating circuits, which are associated with the links capable of forming the different constituent parts of the involved path. For time saving purposes, the crosspoints of each row of the testing arrangement are associated with links of a same type. In this way the number of rows which must be interrogated to detect the condition of the links, capable of forming the involved path, is substantially reduced.

Assuming that row X_{11} of the matrix of FIG. 1 is interrogated and that only the link associated with the crosspoint of row X_{11} and column Y_{11} is in the busy state, the interrogation pulse applied to row X_{11} through scanning circuit SC, will cause the activation of the matrix outputs P_2 to P_k and consequently of the corresponding inputs of register REG via the associated buffer and column amplifiers BA_2 to BA_k and A_2 to A_k . Indeed, the above interrogation pulse, which has an amplitude equal to the DC potential level of source E_2 , e.g. 12 volts, will cause the diodes W_1 of all crosspoints of row X_{11} , except crosspoint X_{11}/Y_{11} thereof, to be brought in the conductive condition since, as aforementioned, the junction point of the resistors R_1, R_2 of a gate associated with a busy or free link is at the ground potential or at a positive potential of E_1 volts, e.g. +5 volts, respectively. The potential of column Y_{11} does not change, so that the buffer amplifier BA_1 and column amplifier A_1 remain in their rest condition and the corresponding bistable device of register REG registers a 0-bit, i.e. it remains in its 0-condition. The potential of columns Y_{12} to Y_{1k} is raised from their bias level of E_2 volts to E_2+E_1 volts (12+5 volts), this potential rise causing the blocking of diodes W_2 associated with columns Y_{12} to Y_{1k} and the conduction of diodes D_{12} to D_{1k} . The above positive potential of E_2+E_1 volts is applied via the conductive diodes D_{12} to D_{1k} to the bases of the transistors Q_1 of the corresponding buffer amplifiers BA_2 to BA_k , thus causing the latter to be switched in the conductive condition. Due to the above transistors Q_1 being conductive, a current path is established from source E_3 , e.g. +48 volts, to ground via resistor R_6 , collector-emitter junction of transistors Q_1 , resistors R_5 and parallel connections of resistors R_8 and capacitors C_4 , respectively. The potential at the base of transistor Q_2 , in each of the column amplifiers A_2 to A_k , becomes more positive than the potential of source E_2 , so that diode W_4 is brought in the blocking condition and transistor Q_2 becomes conductive. Due to the transistor Q_2 , in each of the column amplifiers A_2 to A_k , being switched in the conductive condition, the potential of its collector is lowered, e.g. from 16 volts in the rest condition to E_2 volts (12 volts) in the conductive condition so that a negative going pulse is applied via capacitor C_5 to the base of transistor Q_3 due to which the latter transistor is cut off and its collector potential is raised to E_2 volts (12 volts). In this way the bistable devices of register REG associated to the column amplifiers A_2 to A_k are set to their 1-condition, which means that the above considered $k-1$ links are in their free state. The information thus registered in register REG, is supplied to the above central processor, register REG is reset to zero and a new interrogation order is given to the scanning circuit SC. The interrogation process is continued in the same way as described above, until the central processor obtains the necessary information about the states of the links which are capable of forming the required path.

It is to be noted that the l sets of buffer amplifiers BA_i ($i=1$ to k) respectively associated with the matrix of the arrangement, serve for lowering the output impedances of the corresponding matrices, in order to charge quickly the parasitic capacitances of the input connections of the column amplifiers A_i , which are common to the above l matrices.

Resistors R_7 provide a discharge path for the parasitic capacitances of their associated columns. These parasitic column capacitances mainly constituted by the leakage capacitances of the matrix diodes, are substantially reduced, as it will hereinafter be demonstrated, by means of an ap-

propriate division in groups of rows X_{11} to X_{mn} of each matrix of the testing arrangement.

Calling C the leakage capacitance of each of the diodes W_1 and qC the leakage capacitance of each of the diodes D_{11} to D_{mk} , q being a numerical factor, and assuming that an interrogation pulse is applied to a row of the matrix of FIG. 1, e.g. row X_{11} , the parasitic capacitance Cp of a column, such as column Y_{11} may be written as follows when disregarding row X_1 and diodes W_2 :

$$Cp = \left[n-1 + \frac{qn(m-1)}{q+n} \right] C \quad (1)$$

Indeed, column Y_{11} is charged with the parasitic capacitance $(n-1)c$ of the diodes W_1 of the crosspoints of the $n-1$ noninterrogated rows X_{12} to X_{1n} of group X_{11} to X_{1n} . This parasitic capacitance $(n-1)C$ is in parallel, via conductive diode D_{11} , with the series connection of the parasitic capacitance $q(m-1)C$ of the $m-1$ blocked diodes D_{21} to D_{m1} and the parasitic capacitance $n(m-1)C$ of the $n(m-1)$ diodes W_1 associated with the $m-1$ columns Y_{21} to Y_{m1} .

With mn constant the parasitic column capacitance Cp can be minimized in function of n :

$$\frac{dCp}{dn} = \frac{d}{dn} \left[n-1 + \frac{qn(m-1)}{q+n} \right] C = 0 \quad (2)$$

From the above relation it is derived that Cp is minimum for

$$n = q \left(-1 + \sqrt{1 + \frac{mn}{q}} \right) \quad (3)$$

When mn is large and factor q is close to the unity, relation (3) gives approximately:

$$n \approx m \quad (3')$$

The column capacitance Cp' of a conventional matrix arrangement equivalent to the matrix arrangement of FIG. 1, is given by the following relation:

$$Cp' = (mn-1)C \quad (4)$$

since each column of this conventional matrix with mn rows and k single column conductors, is charged with the parasitic capacitance of the $mn-1$ crosspoint diodes W_1 of the noninterrogated rows.

Comparing the relations (4) and (1) one obtains:

$$\frac{C'p}{Cp} = \frac{mn}{m+n} \quad (5)$$

When integers m and $n > 2$, which is the case for a matrix then,

$$\frac{C'p}{Cp} > 1$$

The above analysis clearly shows the advantages offered by the present diode matrix arrangement with respect to a conventional one.

The aim of the bias $+E_2$ volts applied to the columns Y_{11} to Y_{mk} of the testing arrangement matrices, via the resistors R ($R_3 < < R_2$) and diodes W_2 associated thereto, is to prevent an interrogation pulse from becoming effective for a noninterrogated row, when a diode W_1 pertaining to a crosspoint gate of the latter noninterrogated row is short circuited. Indeed, suppose that an interrogation pulse is applied to row X_{11} , that the link associated with crosspoint X_{11}/Y_{11} is in its free state and that diode W_1 of crosspoint X_{1m}/Y_{11} is short circuited. Then, the +5 volts pulse variation ($E_1+E_2-E_2=+5$ volts) appearing on column Y_{11} , due to the link associated with crosspoint X_{11}/Y_{11} being in its free state, will be transmitted to the noninterrogated row X_{1n} via short-circuited diode W_1 of crosspoint X_{1n}/Y_{11} . This pulse of 5 volts is however of insufficient amplitude to cause any of the other diodes W_1 associated with row X_{1n} to be brought in the conductive condition, since a bias of $E_2=12$ volts is applied to the cathodes of the latter diodes.

Finally, concerning row X_1 of matrix of FIG. 1, an interrogation pulse is periodically applied thereto to check the correct operation of buffer amplifiers BA_i ($i=1$ to k) pertaining to the above matrix, as well as the correct operation of the common column amplifiers A_i . As it may readily be seen, the applica-

tion of the interrogation pulse of +12 volts to row X_1 , will cause the activation of all the k matrix outputs P_1 to P_k and normally all k bistables of register REG must be brought in their 1-condition. In this way, most of the possible failures in column equipments may easily be detected by simple inspection of the content of register REG, after the interrogation of row X_1 . The failures causing the output stages Q_3 of column amplifiers A_1 to A_k to be permanently in their activated condition (+12 volts) are detected by a second inspection of the content of register REG, when the whole testing arrangement is in its rest condition.

While the principles of the invention have been described above in connection with specific apparatus, it is to be clearly understood that this description is made only by way of example and not as a limitation on the scope of the invention.

We claim:

1. A telephone switching system which includes scanning means for interrogating a plurality of links interconnecting a plurality of switching stages of the system and for deriving busy and idle status signals of said plurality of links to be applied to a register means of the system, wherein the improvement comprises a plurality of diode-gating means responsive to said interrogating signals for applying said busy and idle status signals of said links to said register means, each of said diode-gating means being coupled to said scanning means and said register means, and to a corresponding one of said plurality of links, each of said diode-gating means including:

a DC potential source;

a junction;

a first resistive means coupling said DC potential source to said junction;

a second resistive element coupling said junction to said corresponding link;

a capacitive element coupling said scanning means to said junction; and
a first diode means being coupled to said junction and being poled to change from a nonconductive to a conductive state in response to the change in the condition of said corresponding link from an idle to busy condition.

2. The switching system in accordance with claim 1, including a plurality of biasing means, each means establishing a predetermined common bias potential level at the outputs of a selected number of said plurality of gating means.

3. The switching system according to claim 2, wherein said plurality of links generate busy condition signals of different amplitudes, the ratio of said first and said second resistances of each of said plurality of gating means being chosen so that the potentials at the respective junctions are substantially the same irrespective of the differences in the amplitudes of the busy condition signals.

4. The system in accordance with claim 3, wherein said scanning means generates interrogation pulses each having an amplitude substantially equal to said uniform bias potential level.

5. The system in accordance with claim 4, wherein each of said biasing means includes a diode poled opposite to said diode means of said gating means and conducting in response to said gating means detecting said busy status signal of the corresponding link.

6. The system in accordance with claim 5, wherein said plurality of gating means are arranged in a crosspoint gating matrix array of rows and columns, said plurality of biasing means including means for preventing short circuiting of any one of said diode means from affecting other crosspoints.
